INVENTOR

Theodore F. Taylor,

UNITED STATES PATENT OFFICE.

THEODORE F. TAYLOR, OF BROOKLYN, NEW YORK.

TELEPHONE-RECEIVER.

SPECIFICATION forming part of Letters Patent No. 314,155, dated March 17, 1885.

Application filed January 3, 1884. (No model.) Patented in England February 5, 1884, No. 2,703; in France February 5, 1884, No. 106,135; in Germany February 5, 1884; in Belgium February 15, 1884, No. 64,050, and in Canada June 16, 1884, No. 19,531.

To all whom it may concern:

Be it known that I, THEODORE F. TAYLOR, a citizen of the United States, residing in Brooklyn, in the county of Kings and State of New York, have invented certain new and useful Improvements in Telephone-receivers, of which the following is a specification.

The invention relates to the class of instruments employed for translating into corresponding air-vibrations or sound-waves the variations in the strength of an electric current which have been established through the agency of vocal or other sounds.

It is a well-known fact that electric currents when they are caused to traverse neighboring parallel conductors in the same direction exert upon each other an attractive force, and when in opposite directions a repulsive force, and the degree of force with which they so attract or repel is dependent upon the proximity of the conductors and the strengths of the currents. When, therefore, the positions of the conductors are approximately constant, the variations in force may be considered as depending upon the variations in strength. Parallel results are obtained when an electric current is caused to pass through a single electric conductor in proximity to a continuation of itself. Upon this principle the invention is essentially based; and it consists generally in so disposing an electric conductor that different portions of its length are brought into proximity to each other, and a current of electricity caused to traverse the same will pass and repass in approximately parallel directions or in opposite directions through such different portions. Suitable means are provided for supporting such a conductor and for receiving electric connections therewith, so that it may be conveniently included in a telephonic circuit. To this end the conductor is preferably arranged in the form of one or more flat spiral coils.

I am aware that a device has been made and described consisting of a helical coil of resilient wire, or what is commonly called a "spiral spring," one end of which is attached to an iron diaphragm and the other end to a fixed support, and when under proper tension will operate as a telephonic instrument, the spring acting by compression or extension in the line of its axis; but my invention differs essentially

from this, and in no way resembles it. In this device a diaphragm is necessary for the production of sound, while a diaphragm is not a necessary part of my invention. In my receiver a quantity of fine insulated wire is wound upon a flat or approximately flat surface in a "spiral," properly so called—that is, the curves are in one plane, or approximately so, the plane being at right angles to the axis—and this is what is intended to be understood by the term "spiral" or "flat spiral" wherever they are used in this specification. The electric current is then caused to traverse the convolutions of each coil in succession, and thus to exert upon itself an attractive or a repulsive force. This force will vary with the variations in the strength of the current. The flat spiral coils, when more than one are employed, are preferably placed in planes parallel with each other, and they are preferably so connected with each other that a current of electricity traversing the same will pass in parallel or approximately parallel directions through the convolutions of the two or more spiral coils. The parts may, however, be organized to cause the currents to pass in opposite directions through the different coils, and it is not always necessary that the spiral coils be flat, for they may be made convex or otherwise modified in form. The spiral coils are mounted upon any suitable supporting material, which may or may not serve to assist in establishing the acoustic vibrations. Thus they may be secured upon the flat surfaces of resonant plates, such as are now commonly employed in telephonic receivers—or they may be embedded in some glutinous material, such as varnish or shellac. Such an instrument will be found to respond readily and very effectively to the variations in an electric current, which are produced by means of any convenient form of telephonic transmitter. It will be found, also, that a simple spiral coil of wire constructed upon this principle will produce a similar result, though of a less pronounced character. In either case acoustic vibrations will be established by the receiver which correspond to the vibrations whereby the changes in strength of current were primarily occasioned.

In the accompanying drawings, Figure 1 is a plan view, partly in section, of an instru-

ment based upon the principle of this invention; and Fig. 2 is a vertical transverse section of the same. Figs. 3 and 4 are theoretical diagrams illustrating different methods of connecting the coils with each other.

Referring to the drawings, A represents a suitable case, of hard rubber or other suitable material, for supporting the several parts of the instrument. This case may be constructed 10 in the form of a wide ring in two sections, a' and a'' , adapted to be screwed together, as shown, or they may be constructed in any other convenient form.

Within the case A are supported two plates, 15 C' and C'' , which may be of metal, similar to the diaphragms usually employed in the well-known forms of telephones; or they may be constructed of paper, vulcanized fiber, glass, wood, porcelain, or other suitable resonant 20 material. One of the plates, C' , is preferably perforated at its center, as shown at f' , for the purpose of more readily permitting the sound-waves to escape from the interior of the instrument. The plates are separated a slight 25 distance from each other by means of an intervening ring, a^3 , or by any other suitable means. Upon the confronting surfaces of the two diaphragms are placed two flat spiral coils of wire, as shown at c' and c'' , respectively. 30 These coils are preferably secured to the plates by means of a thick varnish or other similar material, and they are connected with each other in such a manner that a current of electricity entering one terminal, d' , will pass 35 through the coils in succession and through the convolutions of the same in parallel directions. The two terminals d' and d'' are secured to suitable binding-posts, e' and e'' , by means of which electrical connections may be conveniently 40 established with the same when the instrument is put in use.

The current employed for operating the instrument may be obtained in any of the usual manners. In practice it will be found convenient to employ some suitable form of transmitter adapted to vary the strength of an electric current comparatively with the sound-waves embodying the words which it is desired to transmit.

50 In Figs. 3 and 4 two different methods of connecting the spiral coils are illustrated. According to the plan illustrated in Fig. 3 the current is caused to enter at the terminal d' and to pass in the direction indicated by the arrows from the exterior to the interior convolution of the spiral coil c' , the direction in each convolution being parallel to the direction in the neighboring convolutions. From the interior convolution the current passes 55 through the connecting portion d'' to the outer convolution of the spiral coil c'' , and in the direction indicated by the arrows through its several convolutions to the terminal d'' . It will be seen thus that the current is caused to 60 traverse both conductors in parallel directions, and the two spiral coils will be attract-

ed toward each other by reason of the attractive force exerted by the current upon itself in the several portions of the conductor. This attractive force is variable by reason of the 70 variations in the strength of the current which are caused by the action of the transmitter. The variations in attractive force thus caused cause a vibration on the part of the receiving-instrument capable of producing sound-waves 75 or sonorous vibrations corresponding to those by means of which the current-variations were originally occasioned.

In Fig. 4 an organization is illustrated in which the connections of the two spiral coils 80 are so changed that the current is caused to traverse the same in opposite directions. Thus the current from the interior convolution of the spiral coil c' passes directly to the interior convolution of the spiral coil c'' , and thence to 85 its outer convolution. The relative directions are thus reversed. The operation of such an instrument is precisely similar to that described in connection with Fig. 3, with the exception that the variations in the repulsive 90 force of the two currents are here availed of, in so far as the two spirals may act upon each other instead of the like variations in the attractive force. The results obtained are, however, essentially the same in either case. 95

Having on January 7 and on January 29, 1884, filed other applications (Serial Nos. 116,624, 116,625, and 119,089) for Letters Patent for certain improvements in telephone-receivers, and having in those applications described certain features involved in this application, I do not herein claim any improvements shown, described, and claimed in either of those applications and not specifically claimed herein. 105

I claim as my invention—

1. A telephonic receiving-instrument consisting of an electric conductor formed into two confronting flat spirals situated in parallel planes, in combination with means, substantially such as described, for placing the same in circuit with a main line. 110

2. A telephonic receiver consisting in the combination, substantially as hereinbefore set forth, of an electrical conductor formed into two confronting flat spirals situated in parallel planes and connected in series, and means, substantially such as described, for supporting the same in position. 115

3. A telephonic receiver consisting of an electric conductor formed into confronting flat spiral coils situated in parallel planes and connected in series, in combination with means for supporting the same. 120

In testimony whereof I have hereunto subscribed my name this 2d day of January, A. D. 1884.

THEODORE F. TAYLOR.
